UNITED STATES PATENT OFFICE

112,728

DESIGN FOR A POWER DRIVEN HAND TOOL UNIT

George A. Weingartner, Fort Thomas, Ky., assignor to The United States Electrical Tool Company, Cincinnati, Ohio, a corporation of Ohio

Application May 17, 1938, Serial No. 77,242

Term of patent 7 years

To all whom it may concern:

Be it known that I, George A. Weingartner, a citizen of the United States, residing at Fort Thomas, in the county of Campbell and State of Kentucky, have invented a new, original, and ornamental Design for a Power Driven Hand Tool Unit, of which the following is a specification, reference being had to the accompanying drawing, forming a part thereof.

The figure is a perspective view of the power driven hand tool unit showing my new design.

The design has substantially the same appearance from both sides insofar as the casing arrangement is concerned. The dominant features in my design reside in the casing portion shown in full lines.

I claim:

The ornamental design for a power driven hand tool unit, substantially as shown and described.

GEORGE A. WEINGARTNER.
